METHOD OF ASSEMBLING BLOCKS AND
STRUCTURE RESULTING THEREFROM

Herbert Alfred Faber, Cincinnati, Ohio

Application March 27, 1936, Serial No. 71,151

4 Claims. (Cl. 72—39)

This invention relates to a method of assembling building blocks, and to the resulting structure.

More particularly the present invention relates to a method of aligning pre-shaped building blocks, and positioning one building block upon a previously placed block, or other suitable supporting structure, to permit a shifting of the later placed, i. e., upper building block in effecting final alignment of component building blocks in the resulting structure.

Embodiments of the present method utilize means arranged upon and between any previously positioned building block, or suitable supporting structure, and the thereon superimposed building block to be aligned, to afford free and easy movement of the subsequently placed building block relative to permanently positioned structure in effecting final alignment therewith, such means, preferably, becoming an integral part of the resulting structure.

A preferred procedure in the present invention includes the positioning of bearing elements, desirably ball bearings of metal, glass, or other suitable material, between receiving means, preferably coordinating grooves provided in respective horizontally contiguous surfaces of adjacent building blocks, the receiving means having been pre-dimensioned and pre-arranged for coordination with each other and the bearing elements, or equivalent, in securing and retaining preliminary alignment of the building blocks. The building block to be aligned with permanently positioned structure is thus mounted for limited movement in two dimensions. Either simultaneously with the placing of bearing means, or upon desired relative adjustments between permanent structure and the block to be positioned being made, insert and spacer blocks of wood, metal, or other suitable material, pre-dimensioned to cooperate with the bearing elements in effecting and/or retaining final alignment of the building blocks, are placed at suitable locations between the building blocks relative to the bearing elements.

Subsequent to final alignment, the clearance between adjacent aligned building blocks may be filled with a self-hardening grouting material, thus grouting and permanizing the bearing elements and insert-blocks relative to one another and the associated building blocks into permanent association with the wall structure.

Further features and objects of the present invention will be more fully understood from the

following detailed description, and the accompanying drawing, in which

Fig. 1 is front perspective view of a preliminary step of coordinating building blocks pursuant to a preferred procedure of the present method.

Fig. 2 is an enlarged vertical section taken through the slab portions, perpendicular to the wall faces thereof, of component building blocks of a structure in final alignment preparatory to grouting or equivalent.

Fig. 3 is a vertical section, on a reduced scale, corresponding to that of Fig. 2, and showing the aligning means grouted into final position.

Fig. 4 is a vertical section, on a reduced scale, corresponding to Fig. 2. This view illustrates the application of my invention to a structure built up of blocks of thick rectangular-slab configuration, as compared with building blocks having stud elements extending therefrom.

Fig. 5 is a detail perspective view of another embodiment of my invention, the indicated parts being shown in exploded relation, for the sake of clarity.

Fig. 6 is a vertical sectional view of the embodiment illustrated in Fig. 5.

Referring to the drawing illustrating certain preferred forms of my invention, and referring in the first instance particularly to Figs. 1, 2, and 3, Fig. 1 illustrates a preliminary step in procedure, 10 indicating a pre-shaped building block permanently positioned in a partially erected structure. Such block 10 is preferably cast, as from concrete, to include a slab body portion 11 and studs 12, 12, integral therewith and extending from a face of same.

Such building block 10 includes on the upper surface, 11a, of its slab portion 11, means for receiving suitable bearing means, the receiving means being advantageously a groove, and desirably a V-groove, as at 13 extending lengthwise, and preferably continuously so, along the top surface 11a of the slab 10, and spaced from the lengthwise edges thereof. The bearing means, cooperating with such groove, or equivalent, are advantageously two or more ball bearings 14, which may be of glass, steel, or other material having suitable load supporting and other pertinent qualifications, such ball bearings 14 fitting into the V-groove 13 and having such diameter as affords a stable seating of each ball in such V-groove and to provide a major portion of each ball to extend out of such groove and above the upper surface 11a, of such block 10, for purposes explained more fully hereinafter.

- Indicated at 15, see Fig. 1, is a building block pre-shaped to conform to the configuration of the stated block 10, the block 15 including similarly, a slab body portion 16 and the stud elements 17, the block 15 having on its lower surface 16a receiving and seating means adapted for coordination with the receiving and seating means of block 10 and the therein inserted bearing elements 14. In the embodiment illustrated in Fig. 1, see also 5 Fig. 2, such receiving means of block 15 takes the form of a V-groove 18, disposed on the lower face 16a of its slab portion 16, in register with the cooperating V-groove 13 of the upper surface 11a of the lower block 10.
- 10 The block 15 is illustrated in Fig. 1 at a stage prior to that of preliminary alignment with permanent structure, inclusive of the block 10. The preliminary alignment is attained by super-imposing the block 15 upon the block 10 with the 15 V-grooves of respective blocks in mutual coordination, the groove 18 being vertically aligned with the groove 13 and with the ball bearings 14 placed in the groove 13, as shown generally at 19, Fig. 2. The ball bearings 14 and coordinated grooves 20 25 13, 18, thus afford any required lateral sliding movement, and/or limited vertical rocking movement to attain the desired block-to-block alignment.

Either simultaneously with the placement of 30 the block 15 upon the ball bearings 14, or subsequent to such placement and to any aligning movement of the block 15 relative to permanently positioned structure, insert blocks 20 are placed at suitable locations relative to the bearings 14, 35 and advantageously between opposing surfaces 12a and 17a of the studs 12 and 17 respectively, of the blocks 10, 15, and desirably at the extremities thereof, as illustrated in Fig. 2. The insert blocks 20 are pre-dimensioned to effect the desired final alignment both horizontally and vertically between the blocks.

Usually, the insert blocks 20 are pre-dimensioned according to the diameters of the ball bearings 14 to effect a clearance, see 21, Fig. 2, 45 between the thus aligned building blocks, which clearance is rectangular in outline, and thus affords true vertical and horizontal alignment of the respective correlated building blocks and attendantly of the structure as an entirety.

50 Subsequent to the final positioning and aligning of such building block 15 upon such building block 10, the clearances 19, 21 may be filled with grouting material 22, or the like, see Fig. 3, and the ball bearings 14 together with the insert blocks 20 grouted into permanent association with the resulting structure.

In the application of my invention to building blocks of thick slab configuration, such as those indicated in vertical section in Fig. 4, a superimposed building block, such as the illustrated block 23, is aligned with respect to a lower building block, such as the block 24, in a manner similar to that described in relation to the stud-provided building blocks 10, 15, shown in Figs. 1, 2 65 and 3. The coordinating grooves 25, 26, of building blocks 23, 24, respectively in such embodiment are desirably located proximate one edge of their respective corresponding faces, and the spacer and retaining blocks 27, are desirably located 70 proximate the edges of the opposite faces of the building blocks. Such insert and retaining blocks 27 may be of wedge formation, as shown.

75 Fig. 5 shows another type of embodiment of my invention, wherein the coordinating receiving means for each bearing, is in the form of a recess

of conical or other general V contour and pre-determined dimensions, in lieu of a groove. Specifically, Fig. 5 illustrates a lowerly disposed block 11' provided at its upper face with the desired plurality of such recesses 13', each receiving and rotatably retaining a bearing ball 14, and upward disposed block 16' provided at its lower face with correlatedly disposed recesses 18', each receiving and rotatably retaining a bearing ball 14.

Whereas I have described my invention by 10 reference to specific forms thereof, it will be understood that many changes and modifications may be made without departing from the spirit of the invention.

I claim:

1. An improved building structure of aligned component building blocks, comprising a plurality of mutually superposed building blocks, ball bearing means interposed between adjacent building blocks to afford desired aligning of correlated building blocks, and means for retaining said ball bearing means and correlated aligned building blocks in position, said retaining means including elements inserted in the clearance between correlated adjacent building blocks.

2. An improved building structure of aligned component building blocks, comprising a plurality of mutually superposed building blocks, ball bearing means interposed between adjacent building blocks to afford desired aligning of correlated 20 building blocks, and means including correlated grooves for retaining said ball bearing means and correlated aligned building blocks in position, said retaining means including elements inserted in the clearance between correlated adjacent building blocks.

3. A method of constructing a building from preshaped building blocks, each provided with means for receiving bearing elements, the said receiving means of respective blocks being located in pre-determined coordinating relation to the receiving means of the other component blocks or of similar receiving means provided in permanently positioned component structure; which comprises preparing suitable foundation 45 structure having receiving means configurated and located suitably for coordination with the receiving means of the preshaped building blocks; placing bearing elements in the receiving means of said foundation structure; positioning, tentatively, preshaped building blocks on said foundation structure with their respective receiving means coordinating with the receiving means of the said foundation structure and with the said bearing elements retained thereby; adjusting 50 the alignment of the tentatively positioned building blocks relative to one another and to the said foundation structure to afford final alignment for the entire structure; permanently tying together the thus aligned structure to prohibit relative movement of the component elements of the structure; and adding preshaped building blocks in like manner, sequentially, to the said aligned and permanently tied structure to complete the said building construction.

4. A method of constructing a building from preshaped building blocks, each provided with means for receiving bearing elements, the said receiving means of respective blocks being located in pre-determined coordinating relation to the receiving means of the other component blocks or of similar receiving means provided in permanently positioned component structure, and comprising recesses formed in appropriate surfaces of the building blocks; which comprises 70
